UNITED STATES PATENT OFFICE.

ARTHUR J. FARMER, OF DETROIT, MICHIGAN.

COPYING-CLOTH FOR TYPE-WRITER PLATENS.

No. 889,918.

Specification of Letters Patent

Patented June 9, 1908.

Application filed February 18, 1907. Serial No. 358,082.

To all whom it may concern:

Be it known that I, ARTHUR J. FARMER, a citizen of the United States, residing at Detroit, county of Wayne, State of Michigan, have invented a certain new and useful Improvement in Copying-Cloth for Type-Writer Platens, and declare the following to be a full, clear, and exact description of the same, such as will enable others skilled in the art to which it pertains to make and use the same, reference being had to the accompanying drawings, which form a part of this specification.

My invention relates in general to manifolding copies of written matter, and more particularly to an improvement in typewriters for producing duplicate copies without the use of carbon paper.

It is customary when it is desired to produce duplicate copies of typewritten matter to interpose a sheet of carbon paper between two sheets of blank paper, the three sheets being then inserted between the platen and copying ribbon. The original copy is made on the outer sheet by the type forcing the ribbon against the same, while the second copy is made by the carbon paper upon the inner sheet owing to the impact of the type transmitted through the outer sheet. This method is objectionable as it requires considerable time to arrange by hand the superposed blank sheets and interposed carbon paper and to then insert the series of sheets in the type-writing machine. The handling of the carbon paper soils the hands of the operator and also frequently soils the inner sheet of blank paper when the series of sheets are placed around the platen.

It has heretofore been proposed to obviate the use of carbon paper in making duplicate typewritten copies by securing around the platen a covering impregnated with copying matter and inserting between the ribbon and platen two sheets of paper, the inner one being transparent so that the characters imposed on the back thereof from the platen may be read through the paper. This method is, however, objectionable as the step by step rotation of the platen brings the same portions of the covering into writing alinement with the type during the successive revolutions of the platen, thereby soon wearing out such portions of the covering while the intermediate portions which are not brought into writing alinement of the type remain un-used. It has also been proposed

heretofore to dispense with the use of carbon paper in making duplicate copies of typewritten matter by providing an endless copying belt surrounding the platen and a guide roller. This method necessitates special fixtures being secured to the machine and also requires a copying belt of a length corresponding to the length of the sheets of paper used.

The primary object of my invention is to provide means for producing duplicate copies of typewritten matter without the use of carbon paper or other copying material interposed between the sheets of blank paper, and which will avoid the objections to the methods above referred to.

A further object of my invention is to provide a typewriter platen with a copying cover secured loosely around the surface thereof which will result in such movement of the covering relatively to the platen that different portions of the covering will be brought into writing alinement with the type during the successive revolutions of the platen, thereby fully utilizing every portion of the covering.

A still further object of my invention is to provide a copying covering for typewriter platens which may be readily inserted in a typewriting machine and secured loosely around the platen thereof.

A still further object of my invention is to provide means for producing duplicate copies of typewritten matter which will be simple in construction, inexpensive in manufacture, and efficient in use.

My invention may be generally described as consisting in providing a flexible covering composed of a fabric impregnated with coloring matter and a stiff flexible backing secured thereto, the width of the covering corresponding to the width of the usual typewriter platen and its size being such that when secured around the platen it will hang loose therefrom and move relatively thereto during the step by step revolutions of the platen.

My invention will be more fully described hereinafter with reference to the accompanying drawing in which the same is illustrated as embodied in a convenient and practical form, and in which

Figure 1 is a plan view of a typewriter platen provided with my improvement; Fig. 2 a sectional view on line 2-2 Fig. 1; and Fig. 3 a perspective view of the covering in

condition to be inserted in a typewriter preparatory to securing the same around the platen thereof.

The same reference characters are used to 5 designate the same parts in the several figures of the drawing.

Reference character A indicates the usual core of an ordinary typewriter platen the ends of which are provided with journals *a*, *a*.

10 B indicates the hard rubber layer surrounding the core such as is provided in the usual form of platen. The particular construction of platen, however, in itself forms no part of my invention, as my improvement is capable of being used in connection 15 with any type of platen, the form shown being merely for convenience in disclosing my invention.

c indicates a flexible covering for the typewriter platen comprising a fabric impregnated with pigment or other coloring matter capable of producing an impression when a blow is received thereon, such for instance as carbonized cloth. In order that the covering 20 may be sufficiently stiff to be readily inserted in a typewriter preparatory to securing the same around the platen, I preferably provide a backing *d* of stiff flexible material, such for instance as paper, to which the carbonized cloth is smoothly secured.

In order that the covering C may be easily inserted in the typewriter it is desirable that the edge thereof which passes around the platen should be folded back as indicated at 35 *c* in Fig. 3, thereby preventing the covering from wrinkling when being inserted between the platen and the usual contacting guiding surface.

Secured to the printing surface of the covering so as to project beyond the fold formed by turning back the portion *c* are fastening devices such as adhesive tabs *c'* and *c''*. The edge of the covering opposite the folded portion is preferably cut along planes intersecting 40 the plane of the axis of the platen as indicated at *C'* and *C''*. The covering C is of a length greater than the circumference of the platen so that when secured around the platen it will be sufficiently loose thereon to 45 permit its moving relatively to the surface of the platen.

The covering is secured around the platen by inserting the folded edge *c* between the platen and the adjacent guiding surface and 50 then rotating the platen so that the inclined edges *C'* and *C''* may over-lap the folded portion *c*. The tabs *c'* and *c''* are then secured to the portions of the covering adjacent the sides of the inclined edges *C'* and *C''*, as 55 clearly shown in Fig. 1. The folded portion *c* which is straightened out after the covering is located around the platen underlies the portion of the covering immediately adjacent the inclined edges *C'* and *C''*.

60 65 After the covering has been secured

around the platen the typewriter machine is used in the ordinary manner, two sheets of paper being interposed between the covering on the platen and the usual typewriting ribbon. The operation of the keys produces 70 impressions from the ribbon upon the outer surface of the outer sheet of paper while corresponding impressions are formed by the type upon the under surface of the inner thin sheet of paper by forcing the same into contact with the platen covering. As the covering loosely surrounds the platen the step by step rotation of the platen permits a movement of the covering relatively to the surface of the platen so that different portions of the covering are brought into writing alinement during the successive revolutions of the platen, thereby utilizing the entire surface of the covering. By providing inclined edges on the over-lapping end of the 80 covering there is no danger of more than two letters in a line of typewriting being obscured by reason of the over-lapping edge of the covering being engaged by the type.

From the foregoing description it will be observed that I have invented an improvement in the art of duplicating typewritten copies by means of which two sheets of paper may be inserted between the usual copying ribbon and a copying covering around a 90 platen thereby obviating the necessity of inserting carbon paper between the sheets of writing paper, the copying covering being loosely secured around the platen so that it will move relatively to the surface of the 100 platen and thereby bring all portions thereof into writing alinement with the type.

Having now fully described my invention, what I claim as new and desire to secure by Letters Patent is:

1. The combination with a revoluble platen of a typewriting machine, of a copying covering loosely surrounding and wholly supported and driven by said platen.

2. The combination with the revoluble platen of a typewriting machine, of an endless copying covering loosely surrounding and wholly supported by and driven from said platen.

3. The combination with a revoluble platen of a typewriting machine, of a copying covering consisting of an endless band of greater length than the circumference of the platen surrounding and wholly supported by and driven from said platen, said band being 115 composed of a layer of fabric impregnated with coloring matter and a stiff flexible backing secured to the fabric.

In testimony whereof, I sign this specification in the presence of two witnesses.

ARTHUR J. FARMER.
